UNITED STATES PATENT OFFICE.

HARRY D. STEARNS, OF SAN FRANCISCO, CALIFORNIA.

DISPLAY AND SERVING RACK.

Application filed January 11, 1922. Serial No. 528,526.

To all whom it may concern:

Be it known that I, HARRY D. STEARNS, a citizen of the United States, and resident of the city and county of San Francisco, 5 State of California, have invented new and useful Improvements in Display and Serving Racks, of which the following is a specification.

My invention is primarily for the purpose 10 of displaying and serving purchasers of small articles and is particularly adapted to the marketing of package goods such as cereals, canned goods, etc., as in groceries. One of the objects of my invention is a plurality 15 of adjustable shelves compactly arranged and with partitions or subdivisions, to keep separate a number of different articles so that any purchaser passing in front of the rack will have before him, on display, the articles which he is likely to purchase 20 and which he may remove from the front of the rack.

A further object is the provision of such 25 a rack wherein the various shelves and subdivisions are replenished from the back.

A further object is a rack such as described and made collapsible for ready transportation and one that may be quickly assembled into a rigid substantial structure.

A further object is a rack as described 30 wherein the shelves and partitions are readily adjustable to suit the various sizes of package goods or merchandise which it is intended to carry, and one therefore that is adapted to the daily and varying requirements of the merchant.

Other objects will appear from the drawings and specifications which follow.

By referring to the accompanying drawings my invention will be made clear.

Fig. 1 illustrates a side view of one form 40 of my rack.

Fig. 2 is a front view of the rack of Fig. 1.

Fig. 3 is a plan cross section of Fig. 1 on the line III—III thereof.

Fig. 4 is a detail of the front corner of one of the shelves and showing the arrangement of the adjustable partition member thereon in perspective.

Fig. 5 is a section through one of the shelves showing the manner of securing the partition in place.

Fig. 6 is a detail of one of the rear corners of one of the shelves in perspective.

Fig. 7 is a detail of one of the front corner brackets with the shelf resting thereon shown in section.

Fig. 8 is a section of one of the corner posts of Fig. 1 on the line VIII—VIII 60 thereof but with the shelf removed. The bracket in this figure being at right angles to the bracket showing of Fig. 7.

Fig. 9 is a detail perspective view of one of the front corners of one of the shelves 65 showing the arrangement of the supporting angle iron and the recess for the bracket pivot of Fig. 8.

Fig. 10 is a fragmentary vertical perspective of one of the supporting corner 70 members showing the bracket supporting strip in place therein and indicating the manner of locking the supporting corner members together independent of the shelving.

Fig. 11 is a detail of one end of one of the cross supports by which the corner members are locked together independent of the shelving.

Throughout the figures similar numerals 80 refer to identical parts.

My rack consists primarily of four or more corner members indicated by the numerals 1, 2, 3, 4. The front members 1, 4, are preferably inclined inward from the vertical. These members are interconnected at their tops and bottoms by suitable cross struts and braces as 5, 6, and each may be fitted to the corner members with any conventional form of fastening. I have found the hook having the taper side 7 adapted to engage over the cross piece 8 well adapted for the members 5, 6, and for the corresponding members at right angles thereto and across the front and back of the rack, the said hook 7 may be passed through a recess 9 to lock the brace in place. Within each of the corner members I rivet or otherwise secure a strip 10 punched with a plurality of openings as 11 spaced close together for the purpose of forming a seat for any adjustable position of the tongue 12 of the corner bracket 13. The said tongue 12 it will be understood is adapted to fit into any of the recesses as 11 and then by tightening the screw 14 against the member 1 the tongue 12 is held in the recess 11 and the bracket 13 thus securely fixed against any vertical movement. The bracket 13 has

100 mounted thereon a pivot or supporting piece 110

15 preferably provided with a flange 16 whereby the shelf is retained from accidentally slipping over the said flange.

5 The assembled frame is adapted to carry a plurality of shelves as 17, which may all be made of the same length and width, or of varying dimensions to suit the tastes and individual requirements of a merchant.

10 Referring particularly to Figs. 4, 5, showing a portion of the shelf 17 in detail it will be seen that the shelves are provided on their fronts with an up extending ledge 19 which is recessed for the passage of a conventional form of stud or other suitable 15 holding means 30 by which the partition 18 may be held in any adjusted horizontal position and clamped therein by the thumb nut 31 against the cooperating slot 20 in the upwardly projecting portion 19 of the shelf 17. 20 The shelves are preferably provided with a supporting strut 21 which I have shown as made of an angle iron and one of the legs of this angle iron is partly cut away at 22 leaving a small portion projecting downward as shown at 25 which locks on to the pivot 15 and over the flange 16. The other leg 24 of the angle iron is riveted to the shelf 17. It is to be understood that both 25 of the front corners of each of the shelves 30 is provided with recesses 22 and the projecting ledge 25 so that the front of each of the shelves is supported on corresponding pivots 15 of the brackets 13 suitably spaced and fixed upon the corner members 1 and 4 35 and with similar brackets mounted upon the corner members 2 and 3 for supporting the rear portion of each of the shelves. At the rear corners of the shelves the supporting angles 21 are correspondingly cut away but 40 over a longer distance so that the bracket pivots 15 extending inward from the corner members 2 and 3 may engage in any portion of the space from the dotted position 26 to the dotted position 27, and the position 45 which these latter pivots will occupy will be dependent upon the slope of the shelf and the position of the shelf in the rack, where-

as the pivots at the front of the shelf will always occupy the dotted position 28 of Fig. 4.

50 It will now be seen that any of the shelves may be placed in any position vertically and at any angle desired and goods placed thereon will slide down against the front upris- 55 ing ledge or plate 19 and may be easily ab- stracted from the front of the rack and as these are abstracted they may be replaced by others from the rear of the rack which will likewise slide down the shelves and 60 against the front ledge 19.

65 The portions 18 may be placed to suit the merchandise and a variety of differently shaped and sized packages may each be con- 70 fined in its own compartment between said partitions and be displayed upon a shelf in a position readily available to purchasers passing in front of the rack.

75 When merchandise of different character is to be displayed the shelving or the parti- 70 tion members 18 may be readjusted to suit the requirements and in this way the greatest quantity and variety of merchandise is at all times on display and offered to serve 75 intending purchasers within a minimum of space.

I claim:

80 A display and serving rack comprising a plurality of supporting members and means for locking said members in spaced relation, each member provided with a plurality of recesses, a corner bracket for each member comprising a frame surrounding said mem- 85 ber with a freedom of movement for said frame, and an inward projecting tongue thereon adapted to engage any recess of the corresponding member, a screw by which 90 said freedom of movement may be restrained when the tongue is engaged in any recess, a plurality of shelves each of greater width than the rack, and a pivot having an enlarged end on said corner bracket and adapted to support one corner of a shelf.

HARRY D. STEARNS.
